HEAD FOR A BARRICADE FLASHER LAMP

Ewing D. Nunn, Jr., 2430 Terraza Place,
Fullerton, Calif.

Filed Mar. 11, 1964, Ser. No. 78,965

Term of patent 14 years

(Cl. D48—24)

Fig. 4.

Fig. 5.

FIG. 1 is a perspective view of a head for a barricade flasher lamp, showing my new design;

FIG. 2 is a side elevational view thereof;

FIG. 3 is a cross-sectional top plan view thereof, taken on the line 3—3 of FIG. 1;

FIG. 4 is a top plan view thereof; and

FIG. 5 is a bottom plan view thereof.

I claim:

The ornamental design for a head for a barricade flasher lamp, as shown.
